(57) **CLAIM**

The ornamental design for vending machine island, as shown and described.

DESCRIPTION

FIG. 1 is a perspective view of a vending machine island;
FIG. 2 is a front view thereof;
FIG. 3 is a rear view thereof;
FIG. 4 is a top view thereof;
FIG. 5 is a bottom view thereof;
FIG. 6 is a right side view thereof; and,
FIG. 7 is a left side view thereof.

The broken lines in the drawings depict environmental structure which forms not part of the claimed design.
